UNITED STATES PATENT OFFICE.

HERBERT J. LA JOIE, OF ORANGE, NEW JERSEY, ASSIGNOR TO AUTOPIANO COMPANY,
A CORPORATION OF NEW YORK.

PLAYER-PIANO FOR PRODUCING SOLO EFFECTS.

1,309,762.

Specification of Letters Patent. Patented July 15, 1919.

Application filed November 27, 1916. Serial No. 133,565.

To all whom it may concern:

Be it known that I, HERBERT J. LA JOIE, a citizen of the United States, residing at Orange, in the county of Essex and State 5 of New Jersey, have invented a new and useful Player-Piano for Producing Solo Effects, of which the following is a specification.

The object of this invention is to provide 10 a player piano with an accenting or solo attachment whereby the theme of a piece of music can be rendered by playing the solo notes louder than the accompaniment or other notes.

15 To accomplish this end, I connect the valves, preferably the secondary valves which control the power pneumatics which operate the actions of a player piano of any approved or standard construction to a series 20 of compartments, and I connect each of said compartments through an always open definitely restricted passage, and also through another opening preferably larger having a valve seat and a controlling valve to the 25 wind chest, preferably by a single wind trunk. These controlling valves are operated by pneumatics controlled from accent openings in the tracker bar. Normally these 30 accent openings are covered by the note sheet, and the pneumatics and valves are arranged so that the controlling valves normally will cover said seats so that the normal communication between said compartments and wind chest will only be through 35 said restricted openings. While this arrangement will allow the same exhaust normally to exist in each of said compartments as exists in the wind chest, when a power pneumatic is called into operation the flow 40 from the chamber will necessarily have to take place through the restricted opening. In other words, while the full exhaust normally will act when the power pneumatic starts in operation, a diminishing effect will 45 be obtained as the flow from the chamber is restricted. Thus a diminished blow is obtained relatively to an unrestricted action of the exhaust in the power pneumatic.

When it is desired to accent any particular note, a perforation is cut in the note sheet to operate the pneumatic to open the valve controlling the other passage between the wind chest or trunk and the particular compartment which connects to the valve of 55 the power pneumatic of the action for the

particular note. Then, when this power pneumatic is called there will be two passages between the compartment and the wind chest, one the restricted passage referred to, and the other through the valve seat, whereby when this condition exists the power pneumatic will be operated for its entire movement with substantially the full exhaust of the wind chest which will give a strong action and loud note as compared 60 with the diminishing action and softer note obtained when the only communication between the compartment and wind chest is through the restricted opening.

By selecting the theme by properly cutting the note sheet, solo effects can be nicely obtained.

The invention also consists of certain improved details and arrangements of construction whereby the invention can be economically applied, and whereby the solo mechanism can be thrown out of operation when it is desired to play the instrument with the ordinary note sheets which are not cut for accenting or solo effects.

One application of the invention is illustrated in the accompanying four sheets of drawings in which—

Figure 1 is a partial front elevation of a player piano with my invention applied thereto;

Fig. 1^a is a small detail of one of the cut-off valves;

Fig. 2 is a top view of the spool box illustrating the valve mechanism for throwing the solo attachment into and out of operation;

Fig. 3 is a plan view of the bottom of the sliding valve;

Fig. 4 is a sectional view taken along the line 4—4 of Fig. 2;

Fig. 5 is a view similar to Fig. 4 showing the sliding valve in a different position;

Fig. 6 is a plan view of a portion of the controlling valve chest;

Fig. 7 is a front view of the parts shown in Fig. 6;

Fig. 8 is an enlarged sectional view on the line 8—8 of Fig. 7, showing one of the accent controlling valves;

Fig. 9 is an enlarged section taken on the line 9—9 of Fig. 1;

Fig. 10 is a front view of a portion of the secondary valve box showing its divisions, and

Fig. 11 is a diagrammatic view of a music sheet, tracker bar, sliding valve, controlling valve chest, and the connections between the same.

- 5 Referring to the drawings and in detail, A designates the spool box in which is arranged the apertured tracker bar B over which the perforated note sheet C is drawn from a music spool or roll held in suitable 10 bearings by the usual take-up roll. The playing apertures are connected by tubes 10 under diaphragms of the usual double primary valves 11. These valves are normally in their lowest positions so as to allow an 15 exhaust trunk 12 to be normally connected through passages 13 to the right of the diaphragms of the usual double secondary valves 14 which control passages 15 leading into the series of power pneumatics 16, which 20 are connected by suitable abstracts and pivoted levers to operate the wippens of the piano actions.

These parts are arranged in any ordinary or preferred way, and as shown they are 25 substantially the parts used in the well-known autopiano illustrated for example in patent to Danquard, No. 766,601, patented August 2, 1904. By these parts the piano will be played from the perforated note 30 sheet in the well-known manner.

My improvement or attachment to the above described arrangement is as follows. The wind trunk D employed for operating the power pneumatics is connected at its 35 ends by pipes 17 and 18 to the wind chest. In the front of the wind trunk D are formed a number of small compartments 19. As many of these compartments are employed as desired, sixteen being used in the present 40 adaptation of the invention, the three right-hand and the three left-hand being connected to act together so that in effect there are twelve of such compartments. Each compartment 19 is connected to the wind trunk 45 D by a small passage 20 (Fig. 8) which is restricted by the conical end of an adjusting or throttle screw 21. Each compartment 19 is also connected to the wind trunk D by another opening 22, preferably larger, which is 50 controlled by a valve 23 normally pressed to close said opening by a spring 24, and the stem of which valve is connected to a diaphragm 25 exposed to the tension in the wind trunk D, and covering a chamber or 55 pocket 26. The pockets 26 are connected by tubes 27 and 28 (Fig. 9) to accent openings or apertures in the tracker bar.

In the specific embodiment of the invention illustrated, the ten middle tubes 27 are 60 connected each to control a single valve 23, while each extreme right-hand and extreme left-hand tube 27 is connected by a channel 29 to control three of such valves, as illustrated in Fig. 6. The valve chest which connects to the secondary valves 14 is divided

by partitions 30, as illustrated in Fig. 10, into a number of compartments to co-act with the compartments 19. In the particular division shown there are eleven of these partitions arranged diagonally so that the space 70 between said partitions will be divided into ten compartments 31, each connected to a group of three secondary valves 14, while the compartment 32 at the right of said partitions will connect to twenty-eight of such 75 valves, and the compartment 33 at the left of said partitions will connect to twenty-six of the secondary valves, as I prefer to use only eighty-four power pneumatics.

The compartments 31 are connected by 80 passage-ways 34 to the compartments 19 while the right and left-hand compartments 32 and 33 are each connected by three of such passage-ways 34 to the three right-hand and three left-hand compartments 19. 85 The compartments 19 and 31, 32 and 33 are thus practically co-extensive. By this arrangement each of the ten middle valves 23 will control the playing of three power pneumatics. The three right-hand valves 90 23, which operate synchronously by reason of the right-hand passage 29, will control the playing of the upper twenty-eight of the power pneumatics, and the three left-hand valves 23, which operate synchronously by 95 reason of the left-hand cross channel 29 will control the playing of the lower twenty-six power pneumatics. This division of the instrument and the application of these parts is very easily made without disturbing the 100 ordinary arrangement, as the power pneumatics are arranged in three banks.

The tracker arrangement is shown in diagram in Fig. 11. The tracker bar has the usual perforations, the guide openings, and the loud pedal opening. Five accent openings 35 are arranged at the left of the tracker arranged two to the left and three to the right of the loud pedal perforation; and seven accent openings 35 are arranged 110 at the right. This can be easily done by cutting down the number of power pneumatics and actions played automatically from the usual eighty-eight to eighty-four, that is, taking off two at each end. In cutting the note sheet, the accent controlling perforations 35^a are set slightly in advance 115 of the playing openings 36.

By the arrangement before described solo effects can be obtained by having the theme 120 of a piece of music played louder than the accompaniment or other notes. The major part of the theme usually comes within the thirty notes controlled by the ten middle valves 23. Each of these valves 23 controls 125 a small unit of three power pneumatics. It is very rare that a note is played with the note above or below the same, and by this division of the parts the theme can be easily selected.

When the theme runs above or below these thirty notes the same can be selected by the right and the left-hand accent openings 35. It will be seen that only a single wind trunk 5 for connection to the power pneumatics is provided which is always connected to the series of compartments through always open definitely restricted passages, and also through the large openings which have the 10 controlling valves 23. By this arrangement the same pressure normally exists in each of said compartments as exists in the wind trunk but when a power pneumatic is called into operation the flow will necessarily have 15 to take place through a restricted opening 20. The full exhaust tension normally existing in any one of said compartments acts to start the power pneumatic into operation, but as the flow from the compartment into 20 the wind trunk is restricted a diminishing pressure will be applied to the power pneumatics, and thus a diminishing blow will be obtained relatively to the unrestricted action if the valve 23 were open.

25 When an accent perforation in the note sheet opens any particular controlling valve 23 there are practically two passages between the respective compartment and the wind trunk, one the restricted passage before referred to, and the other the large passage through the valve seat, so that when this condition exists the power pneumatic will be operated for its entire movement with the full exhaust pressure, which 30 will give a strong action and loud note as compared with the diminishing action and softer note obtained when the only communication from the compartment to the wind trunk is through the restricted opening. 35 Thus, in accent playing, the notes are normally played with the restricted or diminishing action but the solo or thematic notes are played with full exhaust.

The following arrangement is provided 40 so that the instrument can be played with the ordinary note sheets which are not cut for solo or accenting effects. The tubes 27 are connected to a valve board or block 37 secured to the back of the spool box, and 45 the tubes 28 which are flexible are secured to a sliding valve 38 which is fitted to slide on the valve board 37, and which is pressed in contact therewith by a bow spring 39 arranged under a screw 40. The valve 38 50 also has a series of holes 41 cut therein. The sliding valve 38 can be operated by a link 42, lever 43, and handle 44. For accent playing the handle 44 is pushed to the left which will push the valve 38 to the right 55 and will connect the tubes 27 and 28, as shown in Fig. 4. When the instrument is 60 to be played without the accenting effect, the handle 44 is pulled to the right which will draw the valve 38 to the left which 65 will connect the tubes 27 to the atmosphere

through the holes 41. This will let the atmosphere in behind the diaphragms of the valves 23 which thus will be opened, whereby the wind trunk D will be freely connected to all the compartments connecting 70 to the secondary valves, whereby the power pneumatics will be played with full exhaust pressure.

As two pipes 17 and 18 are used to connect the wind trunk D with the wind chest, 75 two cut-off valves 45—45 are employed and are connected by links 46—46, lever 47, and link 48 to the reroll lever. It is desirable to use these two connections 17 and 18 to the wind trunk D as the same will provide 80 for a quick flow from either end of the secondary valve chest. By these arrangements the solo effects before described can be easily obtained.

The particular divisions before recited, 85 while not necessary to the invention, are desirable and are the best now known to me for putting the invention into practice. The ten central compartments, each controlling three power pneumatics as before described, allow for any easy selection of the main part of the theme, while if the theme runs above and below this the compartments 90 32 and 33, each connected to the wind trunk through three valves 23, allow for the 95 other theme or loud notes, and for loud bass or treble effects. This construction is also especially applicable to the instrument before mentioned because the power pneumatics thereof are arranged in three banks. 100

The details and arrangements herein shown and described may be greatly varied by a skilled mechanic without departing from the scope of my invention as expressed in the claims.

Having thus fully described my invention, what I desire to obtain by Letters Patent is—

1. In a player piano, the combination of the actions, a series of power pneumatics and valves for operating the same, a tracker bar, a series of compartments each connected to a group of three valves for the intermediate power pneumatics, two compartments connected to two groups of a larger number of the valves for the power pneumatics above and below the groups of three valves, a wind trunk, a restricted opening from each of said compartments to said wind trunk, a large opening between each of said compartments and wind trunk, valves for controlling said large openings, pneumatics for operating said valves, and accent openings in the tracker bar for controlling the action of said pneumatics.

2. In a player piano, the combination of 125 the actions, a series of power pneumatics and valves for operating the same, a tracker bar, a series of compartments each connected to a group of three valves for the intermediate power pneumatics, two addi- 130

tional compartments connected to control a larger number of the valves for the power pneumatics above and below the groups of intermediate valves, a wind trunk, a restricted opening from each of said compartments to said wind trunk, a large opening between each of said compartments and said wind trunk, there being a plurality of such openings between each additional compartment and said wind trunk, valves for controlling said openings, all of the valves controlling the openings to an additional compartment being connected to operate together, pneumatics for operating said valves, and accent openings in the tracker bar for controlling the action of said pneumatics.

3. In a player piano, the combination of the actions, a series of power pneumatics and valves for operating the same, the tracker bar, a series of compartments each connected to a group of the valves for the power pneumatics, a wind trunk, a restricted opening from each of said compartments to the wind trunk, means for adjust-

ing the restriction of said opening, a large opening between each of said compartments and wind trunk, valves for controlling said large openings, pneumatics for operating said valves, and accent openings in the tracker bar for controlling the action of said pneumatics.

4. In a player piano, the combination of the actions, a series of power pneumatics and valves for operating the same, a series of compartments each connected to a group of the valves for the power pneumatics, a wind trunk, a wind chest, connections from the wind chest to each end of the wind trunk, a restricted opening from each of said compartments to said wind trunk, a large opening between each of said compartments and wind trunk, valves for controlling said large openings, pneumatics for operating said valves, and accent openings in the tracker bar for controlling the action of said pneumatics.

In testimony whereof I have hereunto affixed my signature.

HERBERT J. LA JOIE.
